UNITED STATES PATENT OFFICE.

JOHN E. OSTLINE, OF LIVERPOOL, ENGLAND, ASSIGNOR TO AUTOMATIC ELECTRIC INC., OF CHICAGO, ILLINOIS, A CORPORATION OF DELAWARE.

TELEPHONE SYSTEM.

Application filed June 18, 1926, Serial No. 116,768, and in Great Britain July 30, 1925.

The present invention relates to telephone systems and is more particularly concerned with arrangements for making routine tests of automatic switching apparatus as used in such systems.

The principal object had in mind when the invention was devised was the testing of apparatus employed at a call indicator operator's position for effecting the display of wanted numbers and enabling the operator to complete desired connections, but certain of the principles involved are capable of wider application.

According to one feature of the invention, a testing arrangement for call indicators is provided in which on the performance of a special operation by an operator a definite number is transmitted from the test equipment to the apparatus at the incoming end of a line to operate the recording devices while on the operator plugging into a special jack the various operating features of the cord circuit are automatically tested in turn.

According to another feature of the invention in a testing arrangement for use in telephone systems, an impulse sending switch has its contacts connected to the terminals of a control switch which in accordance with its position is adapted to control the sending of different combinations of impulses.

These features and others not specifically mentioned at this point will be better understood from the following description of a preferred method of carrying the invention into effect, which is given by way of example.

Referring now to the accompanying drawings, comprising Figs. 1 and 2, which when arranged with Fig. 2 to the right of Fig. 1 with the corresponding lines in alignment show one embodiment of the invention which has been designed to work in conjunction with call indicator systems of the type disclosed in my copending applications, Serial #747,373, filed Nov. 1, 1924, and Serial #6,239, filed Feb. 2, 1925. It will however be understood that the invention is not limited to this arrangement and that with comparatively slight modifications, such as would be readily apparent to those skilled in the art, the general principles of the invention could be applied to call indicator apparatus of other types.

The routining apparatus, which may be

common to the exchange, comprises three switches, TS, CS and SS, and a number of relays for controlling their operation. In addition a certain amount of apparatus is provided at each position having access to the routining equipment, this apparatus comprising a switch TRS having access to the trunk relay groups associated with the incoming lines and also apparatus for preventing the common equipment from being taken into use by more than one operator at once. All the switches are preferably 25-point rotary switches with wipers moving always in the same direction, such as are commonly employed as subscribers' individual line switches.

The general operation of the equipment will first be traced through briefly. When a routine test is to be made, the operator removes the plug attached to the headset from the normal jack, thereby busying her position to incoming calls, and inserts it instead in the special jack J¹. If the common apparatus is already in use at this time, she receives a busy tone, but if it is free, she seizes it to the exclusion of other operators. As soon as she obtains access to the equipment, the switch SS is started operating and a particular number is displayed on her lamp panel. She then takes up cord No. 1 and inserts the attached plug into the routining jack J² on the multiple, whereupon she receives ring-back tone indicating two periods of ringing. After this a test tone is heard for a short interval, the cessation of which indicates that the operator may now test the cord for cutouts or other defects. As soon as this is completed, the operator withdraws the plug from the routining jack so as to test the signal for wrong disconnect and then inserts it again, whereupon the re-ringing feature comes into operation and the operator hears ring-back tone during another period of ringing. At the end of this period, the operator hears a different tone, for instance of a much lower frequency, which is to indicate that proper battery-reversal has taken place for metering purposes. This tone ceases after a further short interval, and a disconnect signal then appears on the lamp associated with the cord in use. This lamp is extinguished after a short period and a flashing re-call signal is then displayed. This completes the test of cord No. 1 and the operator ac-

cordingly removes the plug and proceeds to go through the same series of tests with cord No. 2. In the arrangement shown, when the plug is withdrawn at the end of 5 the test, the switch TRS is advanced one step so that the next test is made on the succeeding trunk relay group. Moreover the control switch CS has been advanced so that for the next test a different number is displayed and thus the display lamps and recording apparatus may be tested for all 10 digit values.

Considering now in detail the operation of the apparatus shown, when the operator 15 inserts her headset plug in the jack J^1 , relay 1 is operated in series with the transmitter from ground on the lowest contact of the jack and this relay by operating its armature 2, prepares a circuit for the relay 20 4. If the common equipment is already in use, relay 13 will be operated and armature 16 will therefore not be engaging its back contact so that no circuit is completed for relay 4. Moreover, busy tone is now 25 connected up from the lead BT, armature 15 and its front contact, back contact and armature 11 to the operator's headset so that she receives a busy signal. In case the common apparatus is not in use however, relay 30 4 operates and at armature 7 completes a locking circuit for itself dependent only on relay 1. The operation of armatures 5, 6, 8, 9 and 12 connects the individual apparatus with the common equipment while at 35 armature 11 the circuit for the busy tone is interrupted. Moreover the operation of armature 10 completes a circuit for relay 13, which operates to prepare the equipment for operating, and a circuit is also completed 40 for the interrupter 18 which has a weighted armature 20, and is adapted at its spring 19 to short-circuit itself so that as long as ground is connected up at armature 10, interrupter 18 continues in operation and vibrates at a frequency of, conveniently, 20 45 per second. By the operation of armatures 5 and 6, conductors 39 and 40 extending to the trunk relay group are connected up by way of armatures 32 and 33 and their 50 back contacts, and the normal contacts of wipers 29 and 30 and said wipers to the relay 24, and as conductors 39 and 40 are now connected respectively to battery and ground, relay 24 operates, thereby at its 55 armature 25 completing a circuit for relay 26 which operates also. When the trunk relay group is connected through to the decoder, as fully described in the specifications above referred to, a loop comprising the 60 impulse-responding relays is placed across conductors 39 and 40 instead of the previous battery and ground connections, and relay 24 therefore de-energizes, thereby opening the circuit for relay 26. Since however, this 65 relay is slow-to-release, a circuit is momen-

tarily completed from ground, armature 25 and its back contact, front contact and armature 27, first contact in the bank of wiper 31 and said wiper, vibrating spring 20, winding of rotary magnet 28 to battery. 70 By the operation of magnet 28, the wipers 29, 30 and 31 of the switch SS are now advanced one step, whereupon wiper 31 encounters ground which is connected to the remainder of its bank contacts, and thus 75 the switch SS continues to advance under the control of the vibrating spring 20. The contacts in the banks of wipers 29 and 30 are wired in a particular manner to the wipers 34, 35, 36 and 37 of the control switch 80 CS, to certain contacts of which battery is connected through either high resistance 41 or low resistance 42. The operation of the switch SS therefore serves to send special impulses to the decoder in the manner fully 85 set out in the specifications above referred to, so as to set up the number 1111 on the display lamps. When wiper 31 engages its last contact, instead of finding direct ground it encounters ground through the upper 90 winding of relay 43. Magnet 28 is unable to operate in this circuit, but relay 43 energizes and at armature 45 completes a locking circuit for itself by way of its lower winding and at armature 44 short circuits 95 its upper winding so as to provide direct ground for the operation of the magnet 28. The switch SS is thus returned to its normal position, in which it remains until the 100 test of the particular cord to be employed is completed. Relay 43 moreover, at armatures 32 and 33 disconnects wipers 29 and 30 from the switch TRS so as to prevent a false operation of relay 24 and connects up instead the right-hand winding of the polarized relay 21 and the retardation coil 23 105 in series. The operator upon noting the number displayed upon her lamp panel inserts the plug attached to cord No. 1 into the special test jack J^2 , which as previously pointed out, is located along side those ordinarily used for completing connections to 110 subscribers' lines.

When the plug is inserted in the jack J^2 , a circuit is completed over the sleeve of the 115 plug for the relay 46 which therefore operates; armatures 47 and 48 connect up the operator's speaking set to the trunk conductor; armature 49 opens a point in the circuit of magnet 80 and prepares a locking circuit for relays 43 and 73, and armature 50 removes ground from certain contacts in the bank of wiper 56 for a purpose which will be explained in due course. The operation of the sleeve relay in the cord 120 circuit when the plug is inserted in the jack J^2 starts the trunk finder switch associated with the cord hunting in the usual manner to find the trunk relay group with which 125 the de-coder is associated and when it is 130

found the transmission of ringing current is started. In this case the circuit for the ringing current is from the tip spring of the jack J^2 , armature 65 and its back contact, alternating current relay 50', condenser 52, back contact and armature 60, back contact and armature 66 to the ring contact of the jack. Relay 50' is operated by the ringing current and at its armature 51 completes a circuit for relay 53. Relay 53 upon operating in its turn, at its armature 54 completes a circuit for the stepping magnet 57 of the test switch TS so that this magnet energizes. At the end of the ringing current period, relay 50' deenergizes, thus opening the circuit of relay 53 and when this deenergizes in consequence, the circuit for magnet 57 is opened and it releases and advances the wipers 55 and 56 of the switch TS into engagement with the second contacts in their respective banks.

When the next period of ringing current commences, relay 50' is again operated and when it terminates, relay 50' deenergizes, and, consequently, another impulse is sent to magnet 57 and the switch TS is advanced a further step. Since the operator's speaking set is connected to the conductors 39 and 40, she receives ring-back tone during the ringing periods in the same way as would the calling subscriber. When wiper 56 engages the third contact, the following circuit is completed: ground, armature 17 and its front contact, wiper 55 and the third contact in its bank, upper winding of relay 59 to battery.

Relay 59 is now operated and at armature 60 disconnects relay 50 and places a direct loop across the springs of the jack by way of the secondary winding of the induction coil IC. This corresponds to the reply of the called party and the operator is now given a tone, which extends from a high frequency source over lead HT, front contact 45 and armature 61, armature 74 and its back contact, back contact and armature 71, primary winding of the induction coil to earth. Moreover at armature 62, the interrupter 63 is connected up by way of armature 75 and 50 its back contact so that when the interrupter contacts next close, a circuit is completed for relay 53, which operates as before to advance the wipers of the switch TS one step. When this occurs the circuit for relay 59 is opened and it de-energizes, thereby removing the tone. A circuit is now completed, however, for relay 64 and this relay upon operating at its armatures 65, 66, 67, 68 and 69 changes over the connections to 60 the operator's headset so as to establish the ordinary test conditions for testing the cord circuit for cutouts and similar defects. The operator thus proceeds with this as soon as the circuits are prepared as indicated by the 65 cessation of the tone.

When this test is completed, the operator withdraws the plug, thereby de-energizing relay 46 which at armature 50 completes a circuit for advancing the switch TS a further step. Since the relay 21 is still connected across the line representing a calling subscriber, the signal on wrong disconnect is now given to the operator on the lamp associated with the cord and she then re-inserts the plug. Thereupon the re-ringing 70 feature comes into operation and ringing current is again sent out and this operates relay 50' as before to effect the stepping of the switch TS.

When the wiper 55 engages the seventh contact in its bank, a circuit is completed for the lower winding of relay 59, and also for relay 70. Relay 59 by operating its armature 60 again places a loop across the springs of the jack J^2 , thus simulating the response 85 of the called party but in this case the high frequency tone which was previously connected up at armature 71, is cut off at armature 71 and in its place a low frequency tone from lead LT is connected by way of armature 22 and its front contact, front contact and armature 71, primary winding of the induction coil IC to ground. It should be explained that when the conditions representing the reply of the called party are 90 produced, a reversal of current back over the connection is effected from the cord circuit and this brings about the operation of relay 21. This operation moreover took place in the earlier stage of the test also but 95 was then without effect in connecting up a tone since relay 70 had not been operated. The operator therefore hears now a low frequency tone to indicate that the reversal for effecting metering has taken place satisfactorily. Relay 70 at armature 72 connects up the interrupter 63 to relay 53 so 100 that the wipers of the switch TS are advanced two further steps under the control of the interrupter.

When wiper 55 engages its ninth contact, the circuits for relays 59 and 70 are opened and instead a circuit is completed for relay 73. This relay upon operating, at armature 77 completes a locking circuit for itself dependent upon relay 46; at armature 78 closes a point in the circuit of magnet 80, and at armature 79 alters the locking circuit of relay 43 so as to make it dependent upon relay 46 rather than upon relay 13. Relay 73 moreover at armature 74 disconnects the lead HT; at armature 75 again connects up the interrupter 63 to relay 53, and at armature 76 opens the circuit of polarized relay 21 and retardation coil 23. This operation 115 corresponding to the calling subscriber replacing his receiver; consequently the appropriate lamp associated with the cord circuit in use is now lighted to indicate clearing down by the calling party. When the switch 120 125 130

TS has made a further step owing to the operation of interrupter 63, the following circuit is completed: ground, armature 17 and its front contact, wiper 55 and the tenth contact in its bank, armature 12 and its front contact, winding of magnet 81 to battery. This circuit is opened when wiper 55 makes a further step and magnet 81 then releases and advances the wipers of the switch TRS into engagement with the next trunk relay group. It should be mentioned that the test contacts engaged by wiper 83 are normally left dead, but in case any of the trunk relay sets are not equipped, the test contacts such as 82 corresponding to such sets are connected to ground and it will be seen that when wiper 83 encounters such grounded contacts, a local circuit is completed for magnet 81 over its interrupter contact so that the switch is advanced over such contacts until it reaches the next trunk relay set that requires to be tested.

It should be mentioned also that, though with the arrangements shown a different trunk relay set is employed for each test, this is not essential, and if desired the same trunk relay set could be used for testing with each separate cord. This could conveniently be effected by the use of an additional jack similar to J^2 , the insertion of a plug in which would operate a relay performing similar functions to the relay 46 and in addition opening the above circuit for magnet 81. When the switch TS takes a further step relay 59 again energizes thereby again operating armature 60 and completing a bridge across the tip and ring contacts of the jack J^2 . This corresponds to the called party removing his receiver while his multiple jack is still plugged up and is intended to test the flashing recall feature.

The test is now completed and the operator accordingly withdraws the plug, thereupon releasing relay 46 which at once de-energizes thus opening the circuits of relays 73 and 43. Since relay 73 is slow to release however, the following circuit is now completed: ground, armature 49 and its back contact, armature 78 and its front contact, winding of magnet 80 to battery. Consequently, magnet 80 receives an impulse of sufficient length to cause it to advance the wipers 34-38 of the control switch CS into the next position in which the connections to the bank of the sending switch SS are altered in such a manner that upon the next operation of the switch SS impulses are sent out corresponding to the number 2222. Upon the deenergization of relay 43, which takes place after a short interval, a circuit is again completed at armatures 32 and 33 for relay 24 which accordingly operates and in its turn operates relay 26. Thereafter when the circuit of relay 24 is opened due to the connection of the seized trunk relay

set with the de-coder, the sending switch SS is set in operation and the number 2222 is displayed on the lamp panel.

The operator will now proceed to make the same series of tests with cord No. 2 and thereafter with each of the cords at her position. In case there should be more trunk relay sets than cords and it is desired to test all the trunk relay sets, one or more cords will have to be employed over again. With the wiring of the control switch CS, as shown, the numbers displayed in successive tests are 1111, 2222, 3333 and so on, so that if ten or more tests are made all the indicating lamps are tested.

The leads 84 and 85 extend to a jack adapted to receive a plug attached to a handset with the transmitter and receiver in series. Hence when this plug is inserted relay 86 is operated and at its armatures 87 and 88 connects up the handset in parallel with the regular operator's set.

Having now particularly described and ascertained the nature of our said invention and in what manner the same is to be performed, we declare that what we claim is:—

1. In a telephone system in which line designations are displayed before an operator by means of a call indicator mechanism under control of calling lines, a plurality of cord circuits accessible to said operator for completing connections to lines whose numbers are displayed on said indicator, trunk lines having access to said indicator mechanism, a testing device, means in said device responsive to the performance of a special operation of the operator for automatically seizing an idle trunk line and for automatically operating said indicator mechanism in simulation of actual service conditions to display a definite number, a special test jack associated with said device, and means operable automatically upon the insertion of one of said cords into said special jack for successively testing the various operating features of said cord, simulating the functions of said cord under actual service conditions.

2. In a telephone system in which line designations are displayed before an operator by means of a call indicator mechanism under control of calling lines, a plurality of cord circuits accessible to said operator for completing connections to lines whose numbers are displayed on said indicator, trunk lines having access to said indicator mechanism, a testing device, means in said device responsive to the performance of a special operation of the operator for automatically seizing an idle trunk line and for automatically operating said indicator mechanism in simulation of actual service conditions to display a definite number, said number consisting of a plurality of digits each of the same numeric value, a special

test jack associated with said device, means automatically upon the insertion of one of said cords into said special jack for subjecting said cord to a series of tests in simulation of the functions of said cord under actual service conditions, and means for transmitting an audible check signal to the operator for each test said cord is subjected to. 70

5 features of said cord, simulating the functions of said cord under actual service conditions, and automatic means operable upon the withdrawal of said cord when the test is completed, for associating said testing device with said indicator mechanism over a different trunk line to prepare for a subsequent test.

3. In a telephone system in which line designations are displayed before an operator by means of a call indicator mechanism under control of calling lines, a plurality of cord circuits accessible to said operator for completing connections to lines whose numbers are displayed on said indicator, 15 trunk lines having access to said indicator mechanism, a testing device, means in said device responsive to the performance of a special operation of the operator for automatically seizing an idle trunk line and for 20 automatically operating said indicator mechanism in simulation of actual service conditions to display a definite number, said number consisting of a plurality of digits each of the same numeric value, a special test jack associated with said device, means operable 25 automatically upon the insertion of one of said cords into said special jack for subjecting said cord to a series of tests in simulation of the functions of said cord under actual service conditions, one of said tests 30 being the transmission of ringing current and tripping of the ringing relay in said cord, and means for transmitting a characteristic audible check signal to the operator for each test said cord is subjected to. 100

35 test jack associated with said device, means operable automatically upon the insertion of one of said cords into said special jack for subjecting said cord to a series of tests in simulation of the functions of said cord under actual service conditions, and automatic means operable upon the withdrawal of said cord when the test is completed, for associating said testing device with said indicator over a different trunk line and 40 for automatically operating said indicator to display a definite number consisting of a plurality of digits each of the same but different numeric value from the digits displayed at the previous test, the series of 45 tests applied to a cord inserted responsive to the display of the second number being identical to the one applied to the first cord.

4. In a telephone system in which line designations are displayed before an operator by means of a call indicator mechanism under control of calling lines, a plurality of cord circuits accessible to said operator for completing connections to lines whose numbers are displayed on said indicator, 50 trunk lines having access to said indicator mechanism, a testing device, means in said device responsive to the performance of a special operation of the operator for automatically seizing an idle trunk line and for automatically 55 operating said indicator mechanism in simulation of actual service conditions to display a definite number, said number consisting of a plurality of digits each of the same numeric value, a special test jack, means operable automatically upon the insertion of one of said cords into said special jack for subjecting said cord to a series of 60 tests in simulation of the functions of said cord under actual service conditions, said tests including the transmission of ringing current, the tripping of the ringing relay in said cord, premature withdrawal of the cord, 65 and re-ringing, and means for transmitting a characteristic audible check signal to the operator for each test satisfactorily completed. 120

65 test jack associated with said device, means operable 125

7. In a telephone system in which line 130

5. In a telephone system in which line designations are displayed before an operator by means of a call indicator mechanism under control of calling lines, a plurality of cord circuits accessible to said operator for completing connections to lines whose numbers are displayed on said indicator, trunk lines having access to said indicator mechanism, a testing device, means in said device responsive to the performance of a special operation of the operator for automatically seizing an idle trunk line and for automatically operating said indicator mechanism in simulation of actual service conditions to display a definite number, said number consisting of a plurality of digits each of the same numeric value, a special test jack associated with said device, means operable 80 automatically upon the insertion of one of said cords into said special jack for subjecting said cord to a series of tests in simulation of the functions of said cord under actual service conditions, one of said tests 85 being the transmission of ringing current and tripping of the ringing relay in said cord, and means for transmitting a characteristic audible check signal to the operator for each test said cord is subjected to. 100

6. In a telephone system in which line designations are displayed before an operator by means of a call indicator mechanism under control of calling lines, a plurality of cord circuits accessible to said operator for completing connections to lines whose numbers are displayed on said indicator, trunk lines having access to said indicator mechanism, a testing device, means in said device responsive to the performance of a special operation of the operator for automatically seizing an idle trunk line and for automatically operating said indicator mechanism in simulation of actual service conditions to display a definite number, said number consisting of a plurality of digits each of the same numeric value, a special test jack, means operable automatically upon the insertion of one of said cords into said special jack for subjecting said cord to a series of 110 tests in simulation of the functions of said cord under actual service conditions, said tests including the transmission of ringing current, the tripping of the ringing relay in said cord, premature withdrawal of the cord, 115 and re-ringing, and means for transmitting a characteristic audible check signal to the operator for each test satisfactorily completed. 120

7. In a telephone system in which line 130

- designations are displayed before an operator by means of a call indicator mechanism under control of calling lines, a plurality of cord circuits accessible to said operator for completing connections to lines whose numbers are displayed on said indicator, trunk lines having access to said indicator mechanism, a testing device, means in said device responsive to the performance of a special operation of the operator for automatically seizing an idle trunk line and for automatically operating said indicator mechanism in simulation of actual service conditions to display a definite number, said number consisting of a plurality of digits each of the same numeric value, a special test jack, means operable automatically upon the insertion of one of said cords into said special jack for subjecting said cord to a series of tests in simulation of the functions of said cord under actual service conditions, said tests including the transmission of ringing current, the tripping of the ringing relay in said cord, premature withdrawal of said cord, and re-ringing, means for transmitting a characteristic audible check signal to the operator for each test satisfactorily completed, and automatic means operable upon the withdrawal of said cord when all tests are completed, for associating said testing device with said indicator over a different trunk line and for automatically operating said indicator to display a definite number consisting of a plurality of digits each of the same numeric value but of a different value than the digits displayed at the preceding test, the series of tests applied to a cord inserted responsive to the display of the second number being identical to the one applied to the previously tested cord.
8. In a telephone system, an operator's position, a call indicator for displaying designations of called lines to said operator, a testing device, means for associating said device with said indicator, and means in said device operated automatically upon such associations for successively operating said indicator to display a series of definite and predetermined line designations simulating the functions of said indicator under actual service conditions.
9. In a telephone system, an operator's position, a call indicator for displaying designations of called lines to said operator, a testing device, means for associating said device with said indicator, and means in said device operated automatically upon such association for successively operating said indicator to display a series of definite and predetermined line designations simulating the functions of said indicator under actual service conditions, each designation displayed consisting of a plurality of digits of the same numeric value.
10. In a telephone system, an operator's

position, a call indicator for displaying designations of called lines to said operator, a testing device, means for associating said device with said indicator, and means in said device operated automatically upon such association for successively operating said indicator to display a series of definite and predetermined line designations simulating the functions of said indicator under actual service conditions, each displayed designation being different from the preceding and succeeding designation.

11. In a telephone system, an operator's position, a call indicator for displaying designations of called lines to said operator, a testing device, means for associating said device with said indicator, and means in said device operated automatically upon such association for successively operating said indicator to display a series of definite and predetermined line designations simulating the functions of said indicator under actual service conditions, each displayed designation being different in numeric value from the preceding and succeeding designation, and each designation comprising a plurality of digits of the same numeric value.

12. In a telephone system, an operator's position, a call indicator for displaying designations of called lines to said operator, a testing device, means for associating said device with said indicator, means in said device operated automatically upon such association for successively operating said indicator to display a series of definite and predetermined line designations simulating the functions of said indicator under actual service conditions, and automatic means in said device for determining the numeric value of the designations to be displayed.

13. In a telephone system, an operator's position, a call indicator for displaying designations of called lines to said operator, a testing device, means for associating said device with said indicator, means in said device operated automatically upon such association for successively operating said indicator to display a series of definite and predetermined line designations simulating the functions of said indicator under actual service conditions, and means for automatically changing the numeric value of said designations for each display.

14. In a telephone system, an operator's position, a call indicator for displaying designations of called lines to said operator, a testing device, means for associating said device with said indicator, means in said device operated automatically upon such association for successively operating said indicator to display a series of definite and predetermined line designations simulating the functions of said indicator under actual service conditions, and means for automatically changing the numeric value of said des-

ignations for each display, each designation displayed comprising a plurality of digits of identical numeric value.

15. In a telephone system, an operator's position, a call indicator for displaying designations of called lines to said operator, a testing device, means for associating said device with said indicator, means in said device operated automatically upon such association for successively operating said indicator to display a series of line designations simulating the functions of said indicator under actual service conditions, and means for automatically changing the numeric value of said designations for each display.

16. In a telephone system, an operator's position, a call indicator for displaying designations of called lines to said operator, a testing device, means for associating said device with said indicator, means in said device operated automatically upon such association for successively operating said indicator to display a series of line designations simulating the functions of said indicator under actual service conditions, and means for automatically changing the numeric value of said designations for each display, each designation displayed comprising a plurality of digits of identical numeric value.

17. In a telephone system, an operator's position, a call indicator for displaying designations of called lines to said operator, a plurality of trunk lines having access to said indicator, a testing device, automatic means in said device for successively seizing said indicator over a different one of said trunk lines, and automatic means for operating said indicator upon each seizure to display a line designation in simulation of actual service conditions.

18. In a telephone system, an operator's position, a call indicator for displaying designations of called lines to said operator, a plurality of trunk lines having access to said indicator, a testing device, automatic means in said device for successively seizing said indicator over a different one of said trunk lines, automatic means for operating said indicator upon each seizure to display a line designation in simulation of actual service conditions, and means for automatically changing the numeric value of said designations for each display.

19. In a telephone system, an operator's position, a call indicator for displaying designations of called lines to said operator, a plurality of trunk lines having access to said indicator, a testing device, automatic means in said device for successively seizing said indicator over a different one of said trunk lines, automatic means for operating said indicator upon each seizure to display a line designation in simulation of actual service

conditions, and means for automatically changing the numeric value of said designations for each display, each designation displayed comprising a plurality of digits of identical numeric value.

20. In a telephone system, an operator's position, a plurality of cord circuits for establishing connections between calling and called lines, a testing device, means for associating any one of said cords with said device, means in said device operated automatically upon such association for subjecting an associated cord to a series of functional tests in simulation of actual service conditions, and means for transmitting to the operator a characteristic audible signal upon the satisfactory completion of each test.

21. In a telephone system, an operator's position, a plurality of cord circuits for establishing connections between calling and called lines, a testing device, means for associating any one of said cords with said device, means in said device operated automatically upon such association for subjecting an associated cord to a series of functional tests in simulation of actual service conditions, said tests including the transmission of ringing current, the tripping of the ringing relay, premature withdrawal of said cord, and re-ringing, and means for transmitting to the operator a characteristic audible signal upon the satisfactory completion of each test.

22. In a telephone system, an operator's position, a plurality of cord circuits for establishing connections between calling and called lines, a testing device, means for associating any one of said cords with said device, means in said device operated automatically upon such association for subjecting the associated cord to a series of functional tests in simulation of actual service conditions, including a test for the transmission of ringing current, for tripping the ringing relay, for premature withdrawal of the cord, and for re-ringing, and means for transmitting to the operator a different and characteristic audible signal upon the satisfactory completion of each test.

23. In a telephone system, an operator's position, a call indicator for displaying designations of called lines to said operator, trunk lines having access to said indicator, cord circuits for completing calls to said called lines, a testing device, an operator's telephone, plug and jack switches for associating said telephone with said device, automatic means responsive to said association for extending a connection from said device to said indicator over one of said trunk lines, means responsive to said connection for automatically operating said indicator in simulation of actual service conditions to display a definite poly-digit number with digits of identical numeric value, a special jack switch

for associating one of said cords with said testing device, and automatic means for applying to said cord a series of functional tests in simulation of actual service conditions.

24. In a telephone system, an operator's position, a call indicator for displaying designations of called lines to said operator, trunk lines having access to said indicator, 10 cord circuits for completing calls to said called lines, a testing device, an operator's telephone, plug and jack switches for associating said telephone with said device, automatic means responsive to said association for extending a connection from said device to said indicator over one of said trunk lines, means responsive to said connection for automatically operating said indicator in simulation of actual service conditions to display 15 a definite poly-digit number with digits of identical numeric value, a special jack switch for associating one of said cords with said testing device, automatic means for applying to said cord a series of functional tests 20 in simulation of actual service conditions, and means for differently and characteristically signalling to the operator to indicate the satisfactory completion of each of said tests.
- 30 25. In a telephone system, an operator's position, a call indicator for displaying designations of called lines to said operator, trunk lines having access to said indicator, cord circuits for completing calls to said called lines, a testing device, an operator's telephone, plug and jack switches for associating said telephone with said device, automatic means responsive to said association for extending a connection from said 35 device to said indicator over one of said trunk lines, means responsive to said connection for automatically operating said indicator in simulation of actual service conditions to display a definite poly-digit number with digits of identical numeric value, a special jack switch for associating one of 40 said cords with said testing device, automatic means for applying to said cord a series of functional tests in simulation of actual 45 service conditions, automatic means for transmitting to the operator different and characteristic audible signals upon the completion of each test to indicate the condition of said cord with respect to each test, and automatic means for releasing said indicator upon withdrawal of said cord and for re-establishing said connection over a different one 50 of said trunk lines.
- 55 26. In a telephone system, an operator's position, a call indicator for displaying designations of called lines to said operator, trunk lines having access to said indicator,

cord circuits for completing calls to said called lines, a testing device, an operator's telephone, plug and jack switches for associating said telephone with said device, automatic means responsive to said association for extending a connection from said device to said indicator over one of said trunk lines, means responsive to said connection for automatically operating said indicator in simulation of actual service conditions to display a definite poly-digit number with digits of identical numeric value, a special jack switch for associating one of said cords 65 with said testing device, automatic means for applying to said cord a series of functional tests in simulation of actual service conditions, automatic means for transmitting to the operator different and characteristic audible signals upon the completion of each test to indicate the condition of said cord with respect to each test, and automatic means for releasing said indicator upon withdrawal of said cord and for re-establishing said connection over a different one 70 of said trunk lines.

27. In a telephone system, an operator's position, a call indicator for displaying designations of called lines to said operator, trunk lines having access to said indicator, cord circuits for completing calls to said called lines, a testing device, an operator's telephone, plug and jack switches for associating said telephone with said device, 90 automatic means responsive to said association for extending a connection from said device to said indicator over one of said trunk lines, means responsive to said connection for automatically operating said indicator in simulation of actual service conditions to display a definite poly-digit number with digits of identical numeric value, a special jack switch for associating one of 95 said cords with said testing device, automatic means for applying to said cord a series of functional tests in simulation of actual 100 service conditions, automatic means for transmitting to the operator different and characteristic audible signals upon the completion of each test to indicate the condition of said cord with respect to each test, automatic means for releasing said indicator upon satisfactory completion of said tests and withdrawal of said cord and for re-establishing said connection over a different 105 trunk line, and means for conditioning said testing device to re-operate said indicator to display a poly-digit number with digits of a different numeric value from the digits 110 displayed in the preceding test.

In witness whereof, I hereunto subscribe my name this 1st day of June, A. D. 1926.

JOHN E. OSTLINE.
